US0D1068454S

(12) **United States Design Patent** (10) **Patent No.:** **US D1,068,454 S**
(45) **Date of Patent:** **** Apr. 1, 2025**

(54) **TRAILER FRAME BRACKET**

(71) Applicant: **Harbor Freight Tools USA, Inc.**,
Calabasas, CA (US)

(72) Inventor: **Troy Freeman**, Sweetser, IN (US)

(73) Assignee: **Harbor Freight Tools USA, Inc.**,
Calabasas, CA (US)

(**) Term: **15 Years**

(21) Appl. No.: **29/905,294**

(22) Filed: **Oct. 18, 2023**

(51) LOC (15) Cl. **09-06**

(52) U.S. Cl.

USPC **D8/356**

FOREIGN PATENT DOCUMENTS

WO DM213517 12/2020

Primary Examiner — Cynthia R Underwood

(74) *Attorney, Agent, or Firm* — McAndrews, Held & Malloy, Ltd.

(57) **CLAIM**

The ornamental design for a trailer frame bracket, as shown and described.

DESCRIPTION

FIG. 1 is a top and front perspective view of a trailer frame bracket showing my new design;
FIG. 2 is a front elevation view thereof;
FIG. 3 is a rear elevation thereof;
FIG. 4 is a right side elevation view thereof;
FIG. 5 is a left side elevation view thereof;
FIG. 6 is a top plan view thereof;
FIG. 7 is a bottom plan view thereof; and,
FIG. 8 is a bottom and rear perspective view thereof.
The dashed broken lines in the figures illustrate portions of the trailer frame bracket that form no part of the claimed design.

1 Claim, 5 Drawing Sheets
